UNITED STATES PATENT OFFICE.

RANTHUS B. FOUCH, OF MINNEAPOLIS, MINNESOTA.

DESIGN FOR A MOTOR-VEHICLE NUMBER PLATE.

Application filed January 27, 1928. Serial No. 25,060. Term of patent 7 years.

To all whom it may concern:

Be it known that I, RANTHUS B. FOUCH, a citizen of the United States, residing at Minneapolis, in the county of Hennepin and State of Minnesota, have invented a new, original, and ornamental Design for Motor-Vehicle Number Plates, of which the following is a specification, reference being had to the accompanying drawing, forming part thereof.

The figure is a front elevation of a motor vehicle number plate embodying my design.

I claim:

The ornamental design for a motor vehicle number plate, as shown.

RANTHUS B. FOUCH.
